UNITED STATES PATENT OFFICE.

ROBERT D. TOWNSEND, OF CHICAGO, ILLINOIS.

ENVELOP.

No. 928,410.

Specification of Letters Patent.

Patented July 20, 1909.

Application filed January 15, 1908. Serial No. 410,923.

To all whom it may concern:

Be it known that I, ROBERT D. TOWNSEND, citizen of the United States, residing at Chicago, in the county of Cook and State of Illinois, have invented a certain new and useful Improvement in Envelops, of which the following is a full, clear, concise, and exact description, reference being had to the accompanying drawings, forming a part of this specification.

My invention relates to envelops, its object being to produce an envelop provided with indicating means for indicating whether or not the envelop has been tampered with 15 or opened before reaching the person to whom it is addressed.

In accordance with my invention I run a thread or threads through the gummed area of the flap and this thread may be treated 20 with wax, coloring matter, chemicals, or any other composition which upon being subjected to moisture or heat beyond a certain degree will change its condition to cause indication of the fact that heat or moisture 25 has been applied, and so give evidence that the envelop has been tampered with and either opened or attempt made to do so.

In the accompanying drawing my invention is plainly illustrated, Figure 1 being a 30 rear of a closed envelop showing the detecting means applied, Fig. 2 is a similar view showing the envelop flap opened, Fig. 3 is an enlarged sectional view showing one disposition of a single thread, while Fig. 4 is 35 an enlarged sectional view showing the location of two threads applied by an ordinary sewing machine.

On the flap 1 of an ordinary envelop, the section 2 along the edge is gummed. When 40 the envelop is to be closed, this gummed area is first moistened and then the flap pressed into engagement with the envelop body. The usual method for unlawfully opening the envelop is to subject it to heat or moisture, usually by applying steam thereto, which has the effect of softening the gum to 45 allow opening of the flap. Sufficient gum will remain to again close the envelop, or additional gum may be applied, and this 50 work can be so neatly and skilfully done that it is impossible to detect whether or not the envelop has been tampered with. I, however, run a thread or threads back and forth through the gummed section of the flap, and 55 preferably treat the thread with some composition such as a soluble dye or wax, whose

condition will change when subjected to heat or moisture so that indication will be given that attempt has been made to open the envelop. If wax is used and heat applied, the 60 wax will flow into and spread along the paper of the envelop, and if the wax is colored a very plain indication will be given. When coloring matter or dye is used and moisture applied, the dye or coloring matter will soak 65 into the paper and discolor it and thereby give plain indication.

The thread may be applied in various ways. For example, as shown in Fig. 3, a single thread 3 may be applied with an ordinary running stitch, part of the thread then being on the inside of the flap and the thread having been previously treated with the proper material. The thread may be applied either before or after the gum has been applied, and it is perhaps better to apply it before, as in this case the gum will serve to hold the thread in position and will also form a protective coating over the inner thread sections so that when moisture is applied preparatory to sealing the envelop, the thread will not be sufficiently moistened to cause running of the coloring matter. The best and cheapest arrangement, however, is to apply two threads by means of 85 ordinary sewing machines, this arrangement being shown in Fig. 4. If the flap is sewed from the top, then the outer thread 4 will loop through the successive needle openings 5 and the inner thread 6 will be shuttled 90 through these loops; while if the flap is sewed from the under side, the loop thread will be on the inside of the flap and the straight thread on the outside. By thus sewing in the threads they are securely 95 locked in position. Another advantage with this arrangement is that only the outside thread need be treated, and with this arrangement considerable moisture may be applied to the gummed surface and the inner 100 thread before sufficient moisture will pass through the stitch openings 5 to cause the running of the coloring matter or other material with which the outer thread is treated. In this arrangement, also, the gum may be 105 applied either before or after the sewing of the threads.

The application of the threads need not be continuous, but may be in sections, or any other arrangement thereof may be used. A 110 monogram or seal design may be sewed on the flap in any position, and the threads may

also be applied in positions otherwise than in the gummed areas.

The envelop of my invention can be manufactured very cheaply as the threads can be 5 very quickly and efficiently applied by machinery.

Having thus described my invention, I desire to secure the following claims by Letters Patent:

- 10 1. In an envelop, the combination with an envelop body of a normally open flap, sealing gum applied to the under side of the edge of the flap, and a thread sewn back and forth through the gummed area of the flap, the said thread coming in contact with the gummed surface on one side of the flap and into contact with the ungummed surface on the other side of the flap, the said thread being treated with a substance adapted to 15 mark the material of which the flap and envelop body are made upon the application of moisture and heat thereto.
- 20 2. In an envelop, the combination with a paper envelop body of a normally open flap 25 of the same material, sealing gum applied to the under side of the edge of the flap, and a thread impregnated with a soluble dye-stuff

sewn back and forth through the gummed area of the flap, said thread coming into contact with the gummed surface on one side of the flap and into contact with the ungummed surface on the other side of the flap, whereby the application of moisture to the gummed area of the flap will dissolve the dye-stuff and cause it to mark the flap or envelop 35 body.

3. In an envelop, the combination with a sealing flap, of an adhesive gum applied to the inner surface of said flap near its edge, a thread sewn through said gummed portion, said thread occupying a position partly on the gummed surface of said flap and partly on the ungummed surface, and a soluble dye stuff impregnated in said thread said dye stuff adapted to dissolve and stain 40 45 said envelop on the application of heat or moisture.

In witness whereof, I hereunto subscribe my name this 13th day of January A. D., 1908.

ROBERT D. TOWNSEND.
